CLAIM

The ornamental design for a crossbow stock adaptor plate, as shown and described.

DESCRIPTION

FIG. 1 is a rear-right perspective view of a crossbow stock adaptor plate, showing my new design;

FIG. 2 is a right side view thereof; and,

FIG. 3 is a left side view thereof.

The broken line in the drawings depicts unclaimed environment and portion of the adaptor plate only and forms no part of the claimed design.

1 Claim, 3 Drawing Sheets
